UNITED STATES PATENT OFFICE.

A DOLPH ISAACSEN, OF NEW YORK, N. Y.

EJECTOR FOR INSECT-POWDERS.

SPECIFICATION forming part of Letters Patent No. 297,693, dated April 29, 1884.

Application filed November 8, 1883. (No model.)

To all whom it may concern:

Be it known that I, ADOLPH ISAACSEN, of New York city, in the county and State of New York, have invented certain new and useful 5 Improvements in Ejectors for Insect-Powders, of which the following is a specification.

The invention relates to devices for dusting insect-powders, paris-green, and the like; and the novelty consists in the construction 10 and arrangement of parts, as will be more fully hereinafter set forth, and specifically pointed out in the claim.

The object of the invention is to provide an insect-duster consisting of a powder-receptacle and a blower, in which the receptacle is provided with a screw-cap which connects with the receptacle at its largest diameter, and to which is soldered a nozzle. This nozzle, extending through the center of the cap, has 15 a bayonet-connection with the nose of the bellows, and the portion thereof which projects within the receptacle is perforated to emit jets of air under pressure in different directions into the receptacle, and thus stir up and 20 disintegrate the mass of powder, which is liable to pack closely in the receptacle. This construction provides for the ready filling of the receptacle through an aperture which is the whole diameter of the receptacle. A per- 25 forated diaphragm prevents the powder from packing in and choking the discharge passage or nozzle of the receptacle.

What I consider the best manner of carrying out the invention is fully illustrated in the 35 accompanying drawings, which form a part of this specification.

Figure 1 is a side elevation, certain parts being broken away to better show the construction. Fig. 2 is a central longitudinal section. The reservoir is shown detached and turned into position for filling.

Referring to the drawings, in which similar letters of reference indicate like parts in both the figures—

45 A designates a cylindrical receptacle, having one conical end, a, with a nozzle, a', as shown. Each end is provided with a screw-thread, a², which engages a similar internal thread in the cap B or end piece, a. Projecting through the center of the end cap, B,

is a nozzle, C, which is secured to the properly-tapered wood nose D of a suitable bellows, F, by a bayonet-joint at c'. The portion of this nozzle C which projects within the body of the powder in the receptacle A is perforated at several different points, as seen at c, to provide a multiplicity of jets of air, which serve to stir up the powder. A perforated diaphragm, E, is located in the portion a of the receptacle, and serves to prevent the powder from packing in the nozzle a'. I provide a valve, f, of leather or other cheap and durable material, secured by a screw to the wood of the bellows-nozzle D. This prevents the powder from being drawn backward into the 60 bellows. The receptacle, as thus constructed, allows the ready insertion of the powder by detaching the receptacle from the bellows, by detaching nozzle C from nozzle D, or, preferably, by the removal of the cap B, to which 65 is secured by solder, at b', the nozzle C. Either method gives a large opening to receive the powder rapidly and without scattering it. When the device is in use, the multiplicity of 70 jets of air from the apertures c agitates the 75 powder, however it lies.

I provide exchangeable tips a', which are connected to the conical end a by screw-threads. Whenever desired, the tip a' may be unscrewed 80 from its connection with the nozzle and a new one substituted having a different size or a different form of discharge-orifice. One advantage, due to the tips a' being conveniently detachable, is the facility it affords for emptying them. There is always a liability, particularly with the finest-pointed tips, that sufficient powder will get past the diaphragm E to 85 clog them. In such case they are readily unscrewed and emptied.

I do not confine the invention to the use of 90 insect-powder, strictly so called, or to its use in injecting powder into cracks and recesses in buildings and furniture. I can supply paris-green or analogous material in a powdered condition to the reservoir and use a large nozzle 95 for the discharge and dust powder upon the surfaces of plants in the fields, or in various other situations where a powder is to be distributed.

I claim as my invention—

In combination with a readily-detachable current-inducing means, as F D, and a powder-receptacle having a thread, a^2 , the cap B, having tube C, provided with perforations c, 5 and bayonet-joint c', as and for the purposes set forth.

In testimony whereof I have hereunto set

my hand, at New York city, New York, this 29th day of October, 1883, in the presence of two subscribing witnesses.

ADOLPH ISAACSEIN.
